(57) **CLAIM**

The ornamental design for a mobile phone with a movable back cover, as shown and described.

DESCRIPTION

FIG. 1 is a front perspective view of a mobile phone with a movable back cover showing my design.

FIG. 2 is a front elevation view of the mobile phone with a movable back cover in FIG. 1.

FIG. 3 is a rear elevation view of the mobile phone with a movable back cover in FIG. 1.

FIG. 4 is a left side elevation view of the mobile phone with a movable back cover in FIG. 1.

FIG. 5 is a right side elevation view of the mobile phone with a movable back cover in FIG. 1.

FIG. 6 is a top plan view of the mobile phone with a movable back cover in FIG. 1.

FIG. 7 is a bottom plan view of the mobile phone with a movable back cover in FIG. 1.

FIG. 8 is a front perspective view of the mobile phone with a movable back cover of FIG. 1, wherein the back cover is open, showing my design.

FIG. 9 is a front elevation view of the mobile phone with a movable back cover in FIG. 8.

FIG. 10 is a rear elevation view of the mobile phone with a movable back cover in FIG. 8.

FIG. 11 is a left side elevation view of the mobile phone with a movable back cover in FIG. 8.

FIG. 12 is a right side elevation view of the mobile phone with a movable back cover in FIG. 8.

FIG. 13 is a top plan view of the mobile phone with a movable back cover in FIG. 8; and,

FIG. 14 is a bottom plan view of the mobile phone with a movable back cover in FIG. 8.

(Continued)

The broken lines in the drawings depict unclaimed portions of the mobile phone with a movable back cover, and form no part of the claimed design.
